[57] CLAIM

The ornamental design for a tire inflator, as shown and described.

DESCRIPTION

FIG. 1 is a perspective view of a tire inflator showing my new design;

FIG. 2 is a front end elevational view thereof;

FIG. 3 is a rear end elevational view thereof;

FIG. 4 is a bottom plan view thereof;

FIG. 5 is a top plan view thereof; and

FIG. 6 is a side elevational view thereof.

The cord in FIGS. 2-6 is shown fragmentarily for ease of illustration.
